COMBINED UMBRELLA AND SHEATH

Manfred Bremshey, Mount Royal, Quebec, Canada, assignor to Telesco Brophey Limited, Montreal, Quebec, Canada

Continuation-in-part of design application Ser. No. 14,440, Nov. 13, 1968. This application Dec. 30, 1969, Ser. No. 20,706

Claims priority, application Canada June 5, 1968

Term of patent 14 years

Int. Cl. D3—99

U.S. Cl. D87—1

FIG. 1 is a perspective view of the umbrella sheath partly in dotted lines;

FIG. 2 is an end elevational view looking from left-to-right at FIG. 1, with portions of the carrying strap broken away;

FIG. 3 is a side elevational view;

FIG. 4 is an end elevational view from right-to-left at FIG. 3;

FIG. 5 is a bottom plan view; and

FIG. 6 is a section of line 6—6 of FIG. 1.

This application is a continuation-in-part of applicant's copending application Ser. No. D. 14,440, filed Nov. 13, 1968, now abandoned.

I claim:

The ornamental design for a combined umbrella and sheath, as shown.
